[57] CLAIM

The ornamental design for ear protector plug, as shown and described.

DESCRIPTION

FIG. 1 is a side elevation of an ear protector plug showing my new design;

FIG. 2 is a perspective as seen from the right of FIG. 1; FIG. 3 is a side elevation with portions fragmentarily broken away and shown in section;

FIG. 4 is a rear perspective view of a second modified embodiment of the ear protector plug;

FIG. 5 is a rear perspective view of a third modified embodiment of the ear protector plug;

FIG. 6 is a rear perspective view of a fourth modified embodiment of the ear protector plug; and

FIG. 7 is a rear perspective view of a fifth modified embodiment of the ear protector plug.

FIG. 1.

FIG. 2.

FIG. 3.

FIG. 4.

FIG. 5.

FIG. 6.

FIG. 7.
